CLAIM

The ornamental design for a compartmented bottle or the like, substantially as shown and described.

DESCRIPTION

FIG. 1 is a side view of a compartmented bottle or the like showing my new design;

FIG. 2 is an end elevational view thereof;

FIG. 3 is a plan view thereof;

FIG. 4 is a bottom view thereof; and

FIG. 5 is a cross sectional view taken along the lines and in the direction of the arrows 5—5 of FIG. 1. The side and end not shown are mirror images of FIGS. 1 and 2 respectively.

FIG. 1

FIG. 2

FIG. 3

FIG. 4

FIG. 5
